WILHELM B. BRONANDER, OF MONTCLAIR, NEW JERSEY, ASSIGNOR TO AMERICAN MACHINE & FOUNDRY COMPANY, A CORPORATION OF NEW JERSEY

TOBACCO COMPRESSOR FOR CIGARETTE MACHINES

Application filed October 1, 1932. Serial No. 635,837.

This invention relates to tobacco compressors for continuous rod cigarette machines, its main object being to overcome the difficulties heretofore experienced in making a perfect cigarette rod by providing improved means for gradually compressing the tobacco on the moving wrapper strip to approximately the size and shape of the tobacco core in the finished cigarette rod, before it enters the rod form. With this and other objects not specifically mentioned in view, the invention consists in certain constructions hereinafter fully described and then specifically set forth in the claims hereunto appended.

In the present invention this object is accomplished by placing a compression unit consisting of rotating side disks eccentrically mounted with respect to the central pressure wheel in the path of the moving tobacco layer. This causes gradual compression of the tobacco layer to approximately its final shape thereby producing a uniform tobacco core and taking a corresponding amount of compression work off the rod former which folds the travelling wrapper strip around the tobacco layer to form the cigarette rod this relieving of the cigarette rod former being of great importance in high speed machines.

In the accompanying drawing which forms a part of this specification and in which like characters of reference indicate the same or like parts:

Fig. 1 is a side elevation of the improved compressor;

Fig. 2 is a top view of the same; and

Figs. 3 and 4 are sectional elevations taken on lines 3—3 and 4—4 respectively of Fig. 1, showing the compressing action of the improved unit.

In carrying the invention into effect there is provided a cigarette rod compressor comprising two disks, a wheel between said disks, and an eccentric mount for producing relative movement of said disks and said wheel

when rotated. In the best constructions contemplated the eccentric mount includes a support, an eccentric engaging said wheel and having a hub engaging said disks and secured to said support. In the preferred form of construction there is provided means for

rotating the disks and wheel, including a driving shaft journaled in said hub and connected to one of said disks. In the best form of construction contemplated the disks are connected by studs passing through apertures in the wheel, thereby rotating the wheel with the disks. These various means and parts may be widely varied in construction within the scope of the claims, for the particular device selected to illustrate the invention is but one of many possible concrete embodiments of the same. The invention, therefore, is not to be restricted to the specific construction shown and described.

Referring to the drawing, the bracket 10 is fastened to the frame of the cigarette machine (not shown) and supports a shaft 11 which carries a gear 12 meshing with a gear 13 attached to the shaft 14 which is driven from the main drive of the machine. The shaft 11 carries a sprocket 15 which drives a chain 16 running over a sprocket 17 thus imparting motion to the driving shaft 18. An eccentric mount is provided comprising a swingably mounted arm 19 carried by shaft 11, and a stationary eccentric 20, having a hub secured in the arm 19 and provided with a bore, in which rotates the driving shaft 18. The rotation of shaft 18, through the plate 21 attached to the end of the shaft and disk 22, drives the disk 22; the disk 22 being coupled by means of studs 23 to the opposite disk 24, and the disks 22 and 24 having bores fitted on the hub of the eccentric mount. Thus the rotation of the outer disks 22 and 24, drives the compressor wheel 25, which has a bore fitted on the eccentric 20, by means of the studs 23 engaging in apertures 26 in the compressor wheel 25. By the eccentric relation of the compressor wheel and outer disks the tobacco on the cigarette wrapper strip is first confined and guided by the outer disks and then is gradually compressed by the wheel while confined by the disks.

The tobacco T which is delivered from a feed chute (not shown) falls on the paper strip P, fed from a reel into the trough 27. A tape 28 which is suitably driven by well known means, not shown, guides and propels

the cigarette wrapper strip P through the trough 27 and subsequent parts of the cigarette machine. The traveling tobacco layer T moving in the direction of the arrow, Fig. 1, encounters the rotating compressor wheel 25 and side disks 22 and 24, and is gradually compressed (see Figs. 3 and 4). Having passed the compressor wheel, the tobacco layer T is led through the rod former 29 which folds the paper strip P around the tobacco layer to form the cigarette rod. The tongue 30 of the rod former projects between the disks 22 and 24, and acts as a scraper and removes the tobacco from the compressor wheel. The projecting arm 31 of bracket 10 carries an adjustable screw 32 the end of which bears against a boss 33 of the arm 19, thus providing means for regulating the distance between the compressor wheel and the bottom of the trough 27. By adjusting the angular position of the stationary eccentric 20 the clearance between the compressor wheel 25 and the bottom of the trough may be further regulated, while the outer disks 22 and 24 remain in their same relative position with respect to the compressor wheel since they are turned with the latter by the engagement of their connecting studs 23 with the walls of the apertures 26 in the compressor wheel. It should be noted that these apertures are properly placed to permit the studs 23 therein to drive the compressor wheel continuously clockwise, as viewed in Fig. 1, in any adjusted position of the compressor wheel. It will be obvious that the hub of the eccentric mount must be unfastened from arm 17 to permit this adjustment. In this manner a greater or lesser compressing pressure can be applied to the tobacco layer T by the compressor wheel without changing the position of the disks 22 and 24.

What is claimed is:

1. A cigarette rod compressor comprising two disks, a wheel between said disks, and an eccentric mount for producing relative eccentric movement of said disks and said wheel when rotated.
2. A cigarette rod compressor comprising two disks, a wheel between said disks, an eccentric mount for producing relative eccentric movement of said disks and said wheel when rotated, and means for rotating said disks and said wheel on said mount.
3. A cigarette rod compressor comprising two disks, a wheel between said disks, and an eccentric mount for producing relative eccentric movement of said disks and said wheel when rotated, said wheel having apertures and said disks being connected together by studs passing through said apertures.
4. A cigarette rod compressor comprising two disks, a wheel between said disks, and an eccentric mount for producing relative eccentric movement of said disks and said

wheel when rotated, said mount including a support and an eccentric engaging said wheel and having a hub engaging said disks and secured to said support.

5. A cigarette rod compressor comprising two disks, a wheel between said disks, an eccentric mount for producing relative eccentric movement of said disks and said wheel when rotated, and means for rotating said disks and said wheel on said mount, said mount including a movable support and an eccentric engaging said wheel and having a hub engaging said disks and secured to said support, and said means including a driving shaft journaled in said hub.

In testimony whereof, I have signed my name to this specification.

WILHELM B. BRONANDER.
